CONDIMENT SHAKER

Frederick W. Galvin and Lawrence J. Koch,
St. Paul, Minn.

Application May 13, 1948, Serial No. 26,858

2 Claims. (Cl. 222—142.6)

1

The present invention relates to improvements, structurally and functionally, in condiment shakers, particularly those for table use in one's home and public restaurants, and commonly used for dispensing either salt or pepper, as the case may be.

More particularly, the invention has reference to a single shaker construction characterized by individual, selectively usable chambers, one for salt, and the other for pepper, the construction and arrangement being such that the user may conveniently dispense either salt or pepper, whichever is, at the time, wanted.

The primary object of the invention is to structurally, functionally and otherwise improve upon combination salt and pepper shakers in which containers, defining the individual chambers, are connected together in superposed alignment and in which the products to be dispensed are discharged through a single discharge opening at the bottom of the shaker.

Stated somewhat more explicitly, the invention has to do with a shaker construction having a bottom discharge opening and internal conduit means cooperating properly with the salt and pepper chambers, and embodying fixed and movable sections, the movable section being a plunger and provided with a press-button and functioning not only to deliver to the discharge opening, but to function as a valve, making it conveniently possible for the user to assuredly attain the wanted ends.

Other objects and advantages will become more readily apparent from the following description and the accompanying illustrative drawings.

In the drawings, wherein like numerals are employed to designate like parts throughout the views:

Figure 1 is an elevational view, on a small scale, of a combination or duplex-type condiment shaker constructed in accordance with the principles of the present invention;

Figure 2 is a top plan view of said shaker;

Figure 3 is a bottom plan view of same;

Figure 4 is an enlarged central vertical sectional view, with parts in elevation, taken on the plane of the line 4—4 of Figure 2, and looking in the direction of the arrows;

Figures 5 and 6 are cross-sectional views, taken on the irregular section lines 5—5 and 6—6 respectively of Figure 4, looking in the direction of the arrows.

Referring now to the drawings by distinguishing reference numerals, it will be seen that the container is sectional and embodies three principal sections, namely a base section 8, top or cover section 9 and intervening section 10. The sections are appropriate in proportions and shape, and may be approximately those represented in the drawings. The base section 8 embodies a cylindrical body portion 11 having a suit-

2

able circular base 12, the upper end of said body portion being fashioned into a screw-threaded neck 13 and said body defining a receptacle 14 which is here presumed to contain salt. The common discharge opening for the products, salt or pepper as the case may be, is at the center of the bottom and is denoted 15. The section 8 also includes, at the center of the body portion, an upstanding delivery stem or tube 16, which is rigid, which lines up with and rises vertically from the discharge opening 15, and has its upper end provided with an enlarged conical inlet 17 which also functions as a valve seat. The bore or passage of said stem is denoted at 18. The upper end-portion 17 is on a plane well below the neck 13.

The body portion of section 10 is also cylindrical in cross-section and the bottom of same is provided with a concavity 19. It is also formed with a depending skirt which is fashioned into a screwthreaded neck 20 and this is threaded to the neck 13, thus separably adjoining the sections 8 and 10. The receptacle portion, which is presumed to contain pepper, is denoted by the numeral 21 and the upper end of the body portion 22, which defines said receptacle portion, is provided with a further screw-threaded neck 23, and this is adapted to accommodate the neck portion 24 of the cover 25. Referring again to the body 22, it will be observed that this is provided at its center with a passage or bore opening into a socket defined essentially by an upstanding cylindrical member 26, said socket housing a coiled spring 27. Slidably mounted, partly in the socket and partly in said bore, is a novel plunger unit 28, the lower portion 29 of said unit extending downwardly through the bore and into the salt receptacle 14 where it is provided with an assembling and stop collar 30, and a bevelled lower end 31, the latter constituting a valve and coacting with the valve seat 17. The enlarged upper end portion 32 of the plunger provides a guide which is operable in the socket 26, and which also provides a shoulder for the upper end of the expansion spring 27. The bore through the main part of the plunger, is denoted by the numeral 33 and constitutes the passage whereby pepper from the receptacle 21 is allowed to gravitate downwardly and into the bore 18 for exit through the discharge opening 15. Axially aligned with the plunger is a guide recess 34, and this is formed in the central portion of the cover and serves to accommodate the head-portion 35 of a push-button 36. The head-portion 35 connects, by diametrically opposite struts 37 with the upper end of the plunger body. Incidentally, the upper end of the bore 33 is of conical form, as at 38, to facilitate the dropping of pepper into the passage or bore 33. Also, the underside of the cover is of concaved form, as at 39, to provide a deflecting surface for the pepper. These de-

flecting surfaces 19, on the one hand, and 39, on the other, have been referred to as deflecting domes, and function satisfactorily to assist in shaking and delivering the condiments into the delivery conduit for effective escape through the discharge hole 15.

Briefly, it will be seen that the shaker is characterized by the section 8, which defines a receptacle for salt or the like, together with section 10 which defines a similar receptacle for pepper or the like, the two sections having conduit means made up of the stationary section 16 and the movable or plunger section 23, the latter section being push-button controlled. In addition, there is the cover section 9 which closes the upper receptacle and also provides a satisfactory mount for the plunger unit, the essential part of said conduit means. Normally, the spring 27 pushes the plunger up and separates same from the stationary conduit section 16.

In operation, assuming that the plunger is up (as shown in dotted lines), by catching hold of the shaker and shaking it in an up and down movement, it will be seen that the salt in the receptacle will be dashed against the dome 19 and will, in part, find its way into the discharge bore or passage 18, by way of the inlet 17. Thus, the salt will be delivered through the discharge opening. At this time, the pepper is imprisoned in the receptacle 21 and does not escape. However, by forcing the push-button 36 down and seating the valve 31 against the seat 17, the salt is imprisoned in the receptacle 14 against escape, and the pepper is allowed to discharge by way of the passages 33, 18 and 15, as is obvious.

Reference being had again to the stop collar 39, the primary function of this element is that of a stop. That is to say, when the cover section 9 is separated from the section 10, collar 39 serves to prevent the spring 27 from dislodging the plunger, that is, pushing it completely out of the socket 26.

While we have based the disclosure on the idea that the invention is essentially a combination-type salt and pepper shaker and dispenser, it is obvious that the structure serves to contain and dispense many other dry granular and even liquid products.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice so long as no departure is made from the invention as claimed.

Having described the invention what is claimed as new is:

1. A combination-type condiment shaker embodying a lower section including a body portion having a base provided with a discharge opening and defining a receptacle, said base having an upstanding tubular stem lined up with the said discharge opening, the upper end of said stem being below the plane of the upper end of said body portion and being adapted to deliver a condiment from the receptacle through the stem and to discharge same by way of said discharge opening, a second section including a body portion detachably connected with the first named body portion and formed in its bottom with a concavity providing a deflecting dome to assist in de-

livering condiment into the upper end of said stem, said second body portion defining a second condiment receptacle and having a central guide bore and an upstanding member defining a guide socket, a spring returned plunger slidably in the bore and socket, the lower end of said plunger being lined up with and contactable with the upper end of said stem and functioning as a valve, said plunger having a central passage, the upper end of said passage being conical to assist in delivering condiment from the second receptacle into the passage, a closure connected to the upper end of said section section, the underside of said closure having a concavity forming a deflecting dome for the upper portion of said second receptacle, a push-button slidably mounted in said closure, and means integrally connecting said push-button with said plunger.

2. A combination-type condiment holder and shaker embodying a lower section including a hollow body portion, said body portion having a base at its bottom and being open at its top, said base being provided with a condiment discharge opening, said base and body portion defining a condiment receptacle, said base having an upstanding tubular stem rising into said receptacle and lined up at its lower end with said discharge opening, the upper end of said stem being open and adapted to deliver a predetermined condiment from the receptacle through the existing passage in the stem and through the discharge opening, an upper section also including a body portion, said body portion being detachably connected with the upper end of the first named body portion and having a bottom overlying the upper end of said first named body portion and providing a deflecting surface to assist in delivering condiment into the upper end of said stem, said second body portion defining a second condiment receptacle and having a closure provided with a plunger guide, a plunger slidably in said second-named body with its lower end projecting into the first-named receptacle and lined up with and contactable with the upper end of said stem and functioning as a valve for the stem, said plunger having a central passage, the upper end of said passage being communicable with said upper receptacle, a push button slidably mounted in the plunger guide in said cover, an operating connection between said push button and upper end portion of said plunger, and spring means mounted in said second-named body portion and engageable with the plunger for normally raising the latter and disengaging the valve from contact with said stem.
